United States Patent Office

Des. 215,212
Patented Sept. 16, 1969

215,212

DRONE AIRCRAFT

George Calvin Grogan, Charles Henry Green, and Ronald
McKenzie Beattie, Camarillo, David Armstrong Miller,
Northridge, and Robert Taylor Johnston, Thousand
Oaks, Calif., assignors to Northrop Corporation,
Beverly Hills, Calif., a corporation of California

Filed June 21, 1968, Ser. No. 12,469

Term of patent 14 years

Int. Cl. D12—07

U.S. Cl. D22—17

Fig. 3

Fig. 4

FIGURE 1 is a top view of a drone aircraft embodying our new design;

FIGURE 2 is a left side elevation view;

FIGURE 3 is a rear elevation view; and

FIGURE 4 is a front lower perspective view thereof.

We claim:

The ornamental design for a drone aircraft, substantially as shown.
